CABINET

William M. Menkemeir, Baltimore, Md.

Application November 30, 1955, Serial No. 549,967

2 Claims. (Cl. 312—183)

The present invention relates to a cabinet, particularly for a cabinet for the storage and display of maps, charts, illustrations or the like.

One object of the invention is to provide a cabinet where the maps or charts are always carried open on a panel.

Another object of the invention is to provide a cabinet in which a large number of panels may be stored and individually displayed within a small concentrated area.

A further object of the invention is to provide a cabinet having a storage area and a display area in which the panels may be locked into their storage areas for preventing their unauthorized use.

While several objects of the invention have been pointed out, other objects may appear later as the nature of the invention is more fully disclosed. The invention consists of its novel construction, combination and arrangement of its several parts as described and illustrated in the following specification, in which:

Figure 1 is a side elevation of the improved cabinet.

Figure 2 is a fragmentary sectional view taken along line 2—2 of Figure 1.

Figure 3 is a sectional view taken on line 3—3 of Figure 1.

Figure 4 is an enlarged fragmentary elevational view of a portion of one end of the cabinet.

Figure 5 is a fragmentary sectional view taken along line 5—5 of Figure 4.

Figure 6 is an enlarged fragmentary exploded view partly in section, illustrating the end construction of the cabinet.

A general view of the cabinet is shown in Figure 1 and is referred to as a unit by the letter "C." The cabinet has at least one closed end C' and an open section C". However, the present cabinet is illustrated with two closed cabinets C''' and C' and the open sections C" lying between the two closed sections.

The cabinet is provided with a bottom 1 which is continuous throughout the entire bottom area. Across each end of the bottom are 90 degree angle iron supports 2 and 3, which have each of their horizontal sides secured to the bottom 1 by welding or other suitable means.

The corresponding sides of the angle iron 2' and 3' extend upwardly and support against their faces bar members 8 and 9. Extending through the side portions 2' and 3' of the angle iron and the adjustable bars 8 and 9 are a plurality of apertures. These apertures are shown at 10 and 11 respectively in the bars 8 and 9. These apertures are to receive tightly stretched parallel wires 20 for forming channels along the bottom from one end of the cabinet to the other. Each individual wire is held by an individual clamp as shown at 15. The clamps are provided with small apertures as shown at 16 and 17 in Figure 5 through which the wire is extended. Perpendicular to the wire opening is a threaded hole adapted to receive threaded screws 18 and 19, which when operated will engage and hold the wire. For additional security the wire is bent over and silver soldered

2

as shown at 21 and 22 in Figure 5. Adjacent the top of the cabinet is practically an exact duplication of the structure shown and described in Figure 5 for supporting the same number of tightly parallel stretched wires. The

5 top wires are arranged to correspond with the bottom wires to provide channels along the top of the cabinet to correspond to the channels of the bottom of the cabinet.

The adjustment for the bars 8 and 9 are provided by 10 pairs of machine screws, such as shown at 12 in Figures 4, 5 and 6. The screws are positioned one above and one below the line of holes in the members 8 and 9 through which the wires pass. The bars are provided with several pairs of these screws, particularly near the ends. These machine screws extend through the bar 9 and against the upright portion 3' of the angle iron. By screwing down on these screws the bars, or portions of the bars may be moved outwardly at slightly different degrees to tighten the stretched wires.

20 The end portions of the cabinet are referred to as the closed sections. Each of these sections are preferably provided in addition to the continuous bottom with a closed top 25, ends 4 and 5 which are supported upon members 23, 24, 26 and 27, and sidewalls 28, 29, 30

25 and 31. Hinged adjacent the inner edge of the side walls are doors 35 and 36. These doors are adapted to swing open along a line in a plane with the rear sides 30 and 31. The door is adapted with suitable holes for overlapping the U staples 38, through which a lock may

30 be passed to securely lock the doors closed, as shown best in Figure 2. The sides of sections C' and C" forming the front of the cabinet are provided with pockets 40, 41, 42 and 43 for receiving an information card, which is to be used in connection with the particular illustration to be exhibited.

In Figure 6, it is illustrated specifically how the lower portion of the cabinet is assembled and the location of the wire supporting member. The bottom 1 is secured to one side of the 90 degree angle iron member 3 by screws 6. The wire supporting bar 9 is located adjacent the upright portion 3' of the angle iron.

40 Adapted to slide along the channels formed by the stretched wires are a plurality of display boards as shown in Figure 1 by the numeral 45. These display boards are usually constructed from well known "Masonite" board, about which is preferably placed a metal bead 46. On the bottom edge of this display board are a pair of round headed screws 47 and 48. These screws are for supporting the weight of the board along the bottom and act as skids upon which the board is moved out and in the closed sections to and from the open section of the cabinet.

45 The stretched wires at the top of the cabinet are so located in respect to the height of the cabinet that the display board may be raised upwardly from the bottom channel and removed, as shown in Figure 3.

50 The cabinet is equipped with a bonnet 51 along the front edge of the open area under which suitable lighting may be placed in order to light up the board when the contents thereon are being displayed.

55 In operation, starting with the display boards being in the end sections, the doors 35 and 36 are opened, if not already open, until they are in a plane with the rear side 60 of the cabinet. The display boards 45 are marked with tabs 50. The board to be displayed is selected from the tab and the board is pulled from the closed section into the open area between the two sections as shown in Figure 1, where it may be viewed. The board is guided along the channels formed by the tightly stretched wires at the bottom and top of the cabinet. When the operation is completed the boards are moved into the end or ends of the cabinet and the doors are locked by inserting

a lock element through the U-shaped staples after the door slots have been first placed over the staple 38.

While the cabinet is shown as having two closed sections, the cabinet may be constructed with only one closed section, of course, its capacity would then be only one half of its present capacity.

While the invention is described and illustrated for a specific form of cabinet, other forms may become apparent to one skilled in the art, therefore, the present disclosure is not intended as a limitation, as the scope of the invention is best defined in the depending claims.

I claim:

1. In a cabinet including a continuous rigid bottom throughout its entire width and length having at least one section adjacent one end and above said bottom having a length of substantially one half the length of the bottom enclosed by a fixed top, two side walls and an outer end, the inner end of the enclosed section above the said bottom being removable, the area of the open end of the cabinet being of at least the same area as that of the outer end of the closed section, a plurality of tightly drawn parallel wires extending throughout the length of the bottom and fixedly positioned slightly above the said bottom, and corresponding parallel tightly drawn wires extending throughout the length of the cabinet and the

bottom adjacent the top of the cabinet, parallel and equal distance from the bottom wires, for forming corresponding channels between the top and bottom wires for guiding a display board supported on its edge on the bottom of the cabinet in a vertical position as it is moved back and forth over the bottom and in and out of the closed area, said tightly stretched wires are secured across the cabinet by an adjustable bar and individual clamping means at each end of each wire supported by the bar adjacent the outer surface thereof.

2. In a device as set forth in claim 1 in which a hinged door is hingedly supported adjacent the inner edge of each of the rear side walls adjacent the open area and of such dimensions as to close off the area between the open area and the end cabinets when the doors are swung toward the opposite side walls thereof, preventing the movement of the display boards out of the closed sections when the doors are closed.
